1 Claim. (Cl. 179—115.5)

My invention relates to improvements in electrodynamic loud-speakers and microphones. It is a well known fact that, as concerns its fundamental components, the structure of a loud-speaker is the same as that of a microphone, the two types of apparatus differing chiefly by the direction of operation: the loud-speaker produces vibrations of the atmosphere under the action of the electric oscillations to which it is subjected whereas the microphone operates in a reverse manner and produces electric oscillations under the action of vibrations received from the outer atmosphere. Apart from certain details in structure which are well known per se for anyone skilled in the art, it is possible to consider the microphone as the reverse of the loud-speaker and a large number of technical arrangements which are applicable to one type of apparatus are also applicable to the other for reversed operation. For this reason and with a view to greater clarity, I will no longer mention microphones as such in the present specification while the expression "loud-speakers" is intended to convey also the meaning "microphones" so that the reference to microphones should be implicitly understood after each expression "loudspeaker."

It is also a well-known fact that a loud-speaker includes two chief components of which one is transducer, that is an arrangement which transforms electric oscillations into mechanical vibrations, while the other component is constituted by a diaphragm which transmits and diffuses the mechanical oscillations passing out of the transducer to the outer atmosphere.

It is a well-known fact that various types of loud-speakers are known in the art, and electrodynamic loud-speakers are those wherein the transducer is electrodynamic, that is, it resorts to the effects of a magnetic field on a current, with a view to transforming oscillatory electric energy into vibratory mechanical energy or reversely in the case of microphones, in accordance with the well known law of Laplace.

The transducer forms furthermore the driving means for the loud-speaker and its effects are transmitted to the atmosphere through the agency of the diaphragm. The problems to be solved by those skilled in the art for such a transducer or driving means have, generally speaking, been already solved in a comparatively satisfactory manner. The case is not the same for the problems relating to the diaphragm and chiefly to the manner of shifting the driving means with a view to obtaining through the agency of the diaphragm, a shifting of the largest amount of air possible, with a maximum fidelity. Generally speaking, the diaphragm has been hitherto constituted by a cone of paper or the like material, the area of which adjacent the apex is made rigid with an electric winding forming part of the transducer, while the surface of said cone has a remaining area which is generally equal to one or more square decimeters, so as to provide for the shifting of a sufficient amount of ambient air.

The operation of such a system would be theoretically accurate if all the points of the cone were to move in unison with the movable section of the driving means. But, in practice, the case is different, chiefly for the high frequencies of the acoustic spectrum; this is ascrib-

2

able to numerous reasons which it is not necessary to disclose in the present specification, since anyone skilled in the art is well acquainted therewith.

My invention has chiefly for its object, to provide 5 loud-speakers or microphones which satisfy better than those employed heretofore the various requirements appearing in practice, and chiefly, they include diaphragms which are more faithful and/or more efficient, or are more advantageous than the known diaphragms.

10 My invention has for its object to provide a loud-speaker or microphone of an electrodynamic type, which includes at least one magnet generating a magnetic field acting on at least one conductive part such as a wire or ribbon which is rigidly secured to the actual diaphragm ensuring a coupling between said wire or ribbon on the one hand, and the surrounding air on the other hand. Said diaphragm is made of a non-conductive material the thickness of which is sufficient for eliminating practically any elasticity within the range of accelerations and/or stresses appearing in the loud-speaker or microphone, said material having furthermore a specific weight which is under 0.1 and even, preferably under 0.02.

According to my invention, such a loud-speaker is advantageously characterized by the fact that said conductive wire or ribbon is laid on the so-called rear surface of the diaphragm which surface faces the magnet or magnets, while at least 50%, and even preferably at least 90% of the length of said ribbon, wire or the like conductive part, is inserted in the actual gap of said magnet or magnets.

25 The material used for the diaphragm and referred to hereinabove is advantageously a synthetic resin, preferably in an expanded condition which bestows it with an extremely low specific weight and more particularly the material preferably is expanded polystyrene.

30 In a preferred embodiment, the diaphragm of such a loud-speaker or microphone has a large front surface with reference to its thickness, while the major part of its rear surface is rigid with the movable elements of the transducer or driving means of the loud-speaker or the like, said movable elements being substantially linear. The thickness of the diaphragm is preferably between 3 and 12 millimeters.

35 On the other hand, the material forming the diaphragm 40 and the thickness of the latter (excluding any possible projecting section carrying the conductive wire, ribbon or the like part), are advantageously such that any force applied to the rear surface of said diaphragm excluding such possibly projecting sections may, within the range 45 of accelerations and/or stresses appearing normally in loud-speakers and microphones, be transmitted without any substantial deformation to any point of the front surface of the diaphragm which extends within an angle 50 of less than 50° to either side of the perpendicular to said rear surface, passing through the point of application 55 of the force to be considered.

According to a particular embodiment of the invention 60 which seems to be of special advantage, the coupling is performed, by means of a conductive ribbon or wire, which is given longitudinally the shape of a curve representing rectangular relaxation oscillations, which curve is termed hereinafter a Greek pattern. Said ribbon is rigidly secured to the diaphragm. The front surface of 65 the latter may assume any desired outline, but preferably it has a rectangular outline, the length and breadth of which are several times the thickness of said diaphragm. The various sections of the Greek pattern are however energized all simultaneously by a number of magnets, the poles of which extend over a line the length of which 70 is greater than their spacing. Said conductive ribbon or wire is carried on the rear surface of the diaphragm, as

for example on projections, webs or the like members, which engage the gaps of the magnet system so that during the movements of the diaphragm, said ribbon or wire moves in a substantially homogeneous magnetic field.

My invention will be readily understood upon a reading of the following disclosure relating to embodiments illustrated in the accompanying drawing, which includes diagrammatic views of said embodiments and wherein FIGS. 1 and 2 are sectional views, respectively through line I—I of FIG. 2 and line II—II of FIG. 1 of a loud-speaker in accordance with a preferred embodiment of my invention.

FIG. 3 is a partial detail view on enlarged scale of the loud-speaker illustrated in FIGS. 1 and 2.

FIGS. 4 and 5 are respectively a transverse sectional view and a lateral elevational view of the chief components of a loud-speaker wherein the coupling is performed by means of a rectilinear ribbon.

FIGS. 6 and 7 are detail views at right angles with each other and showing means for connecting the conductive ribbon of FIGS. 4 and 5.

FIG. 8 is a view similar to FIG. 4 for the case where the coupling is obtained through two movable parallel ribbons.

FIGS. 9 and 10 are two partial cross-sectional views at right angles with reference to each other, respectively taken along lines IX—IX of FIG. 8 and lines X—X of FIG. 8.

FIG. 11 is a plan view from underneath of a coupling system having a large area which is started vibrating by a conductive ribbon in the shape of a Greek pattern.

FIG. 12 is a corresponding view along line XII—XII of FIG. 11.

FIGS. 13 and 14 are partial views respectively in transverse cross-section and viewed through the rear surface of the diaphragm of the main components of a loud-speaker wherein the coupling is obtained through a plurality of windings.

It should be understood that these figures and the corresponding parts of the disclosure are given solely by way of example, and by no means in a limiting sense.

In the various figures, the following elements of the embodiments illustrated, which play the same part, have received the same reference numbers followed by an alphabetic index which differs from one figure to another. Thus,

The reference number 1 designates my improved diaphragm,

The reference number 2 designates the movable conductive section of the driving means or transducer, which movable section is rigidly secured to said diaphragm 1,

The reference numbers 3 and 5 designate the poles or fractions of a pole of the transducer-energizing magnet or magnets which have the same polarity,

The reference number 4 designates the pole of such a magnet, the polarity of which is opposed to that of the poles 3 and 5,

The reference numbers 6, 7, 8 and 9 designate the sides of the transverse cross-section of the diaphragm, 6 designating more particularly the so-called front side, 7 the rear side which may be omitted, 8 and 9 the lateral surfaces extending between the front surface and the movable section of the driving means,

The reference numbers 10 and 11 designate the parts (such as a ribbon, wire or winding, and the like . . .) feeding current to the conductive means in the movable section 2 of the driving means,

Lastly the reference numbers 12 and 13 designate the suspension or carrier members for the diaphragm 1.

Starting from these data which are the same for the different embodiments illustrated in the drawings, I will now disclose more specifically each of said embodiments.

Turning first to FIGS. 1 and 2, the diaphragm 1a of said embodiment is constituted by a plate or sheet of expanded polystyrene, the specific weight of which is 0.013

to 0.015 gram per cubic centimeter, and the size of which is 81 mm. along its breadth l , while its length L is 120 mm. and its thickness $e1$ is equal to 6 mm. Inside said sheet or plate 1a, there are provided (for instance by a set of cutters) sixteen parallel grooves or slots 14, the depth of which is equal to 4 mm. and the breadth of which $l1$ is equal to 4 mm. Said grooves are thus separated by projections or webs 15, the breadth $l3$ of said webs being equal to 1 mm. The front surface of the coupling means thus formed is shown at 6a while its rear surface 7a includes the webs 15. Over the outer free edges of said webs 15, there is positioned and secured a conductive wire 2a, the cross-section of which may be round or flat. Said wire which is advantageously of aluminium is in the case considered, a round wire of a diameter of about 0.5 mm. Preferably, the wire 2a is previously subjected to the action of a template which gives it the shape of a Greek pattern (as shown at 2g, 2h, 2i . . . etc. . . . in FIG. 11) while one of the surfaces of said Greek pattern, and possibly also the free edge of the webs are coated with a suitable glue, so that the positioning and the securing of the continuous wire 2a over the successive webs 15, may be obtained accurately and rationally. This latter gluing operation is performed advantageously by means of the above-mentioned template. When the glue has set, the template is removed, and the ends of the wire 2a are connected with yielding conductive braids 16 or the like adapted to provide the desired electric connections of the wire.

At the two ends of the diaphragm 1a (FIG. 1) considered longitudinally, there are assembled, for instance through gluing, two tongues 12a, 13a which provide for the suspension of the diaphragm 1a with reference to the frame 18a-18b-25a-25c of the arrangement. This ensures an accurate positioning of the diaphragm, whereby its teeth or webs may engage freely the magnetic gaps formed in the transducer; said gaps are provided in the manner disclosed hereinafter, in a manner such that said webs may move inside said gaps and execute a rectilinear translational movement (in the vertical direction appearing in FIG. 2), whereby they carry along with them the diaphragm 1a with which they are rigid. It is therefore of interest for said suspension tongues 12a, 13a to be sufficiently yielding, so that they may bend in the vertical direction appearing in FIG. 1. As to the materials, shapes and sizes to be selected for said tongues, I may mention as more particularly favorable, the use of polyvinyl chloride or Polyurethane, preferably in an expanded condition, and the sizes of which are in the example considered, a length of 81 mm., a breadth $l2$ of 8 mm. and a thickness of 2 mm. These tongues connect, in the present case, the diaphragm 1a with two metal members 19a, 19b having a square shaped cross-section. Said members 19 may be disconnected, and adjusted with reference to the frame 18a, 18b, 25a, 25b of the arrangement. Insulated conductive terminals 20a, 20b, pass through said members 19 and ensure the feed of current to the conductive braids 16.

The magnetic circuit of the transducer or driving means includes in the embodiment described magnetic slots 21, the number of which is equal to that of the webs 15, and consequently, in the present case, their number is equal to seventeen. Each of said slots is provided with a useful gap of which the sizes are: breadth $l4$ (FIG. 2) 2 mm.—height h (FIG. 2) 4.5 mm., length (FIG. 1) 118 mm. The field in each of said gaps is equal to about 2,000 gauss, and is obtained as follows:

Between two blades 22 and 23 of a highly magnetic metal sheet, of a thickness of 0.5 mm., of a length of 118 mm. and a breadth of 20 mm., there is assembled through gluing a plate 24 of magnetized magnetic ferrite having a high coercive power, with a size of 120 x 16.5 x 2 mm. As particularly apparent from inspection of FIG. 1, said plate projects by 1 mm. beyond the small blades 22 and 23 along three of the sides of the latter, whereas on the

fourth side, that is, at the upper side in FIG. 2, there is provided between the successive blades 22 and 23 a useful gap forming a sort of slot 21. Finally, the blades 22 and 23 form through their upper edges the poles 3 and 5 of the energizing magnets.

As far as the details of execution of the magnetic section of the arrangement are concerned, it seems of advantage to proceed as follows: firstly seventeen members which are identical with that which has just been described are executed, each including two small blades 22 and 23 and a small ferrite plate 24. These seventeen members are then assembled with a spacing between them of 2 mm. which allows the free flowing of air behind the diaphragm that is, at the lower ends of FIGS. 1 and 2 by means of two comb-shaped structures 25a and 25b advantageously of aluminum including the desired corrugations or flatlings, for engagement over the outwardly projecting ends of the different ferrite plates.

These two combs 25a and 25b serve as stays for the longitudinal angle bars 18a, 18b (FIG. 2) which form with said combs 25a and 25b the above-referred to frame of the loud-speaker. The whole arrangement is designed furthermore in a manner such that the webs 15 of the diaphragm are inserted each substantially at mid-height into the corresponding gap or slot 21 and thereby the wire 2a is adapted to move in a magnetic field which is unvarying during the movements of the diaphragm.

As already mentioned, the above described embodiment illustrated in FIGS. 1 to 3, may be subjected within the scope of the accompanying claims to various modifications, of which a number are disclosed hereinafter.

According to a first modification which is very advantageous in many cases, instead of the webs 15 carrying a conductive element constituted by a wire, there is provided a conductive element constituted by a metal structure, also in the shape of a Greek pattern cut in a thin plate, preferably of aluminum and glued flatwise over the free edges of said webs, as clearly shown in FIG. 3. This may lead to an easier or more convenient machining, taking into account the desired accuracy to be obtained. It may furthermore be preferable to give the breadth 13 of the corresponding webs of the diaphragm a value generally larger than 1 mm., say about 2 mm.

According to a further modification, instead of producing a winding which in practice extends in an unvarying direction between the two braids 16, there are formed, for instance by means of a template, windings including a plurality of forwardly and rearwardly directed sections of a conductive wire which is then generally of a smaller diameter than the wire 2a. This allows obtaining driving or transducing members of which the impedance may be higher than in the embodiment illustrated in FIGS. 1 and 2.

According to a still further modification, there are produced in a similar manner, two or more windings which are mechanically associated but are electrically insulated from each other, for instance with a view to tapping off a counter-reaction voltage adapted to control the transducer and the associated amplifier. Such a counter-reaction system would be of no interest in the case of conventional loud-speakers because the movements of the cone provided in the latter have no accurate relationship with the movements of the driving windings. The case is quite different in the case of a loud-speaker according to my invention, wherein the movements of the diaphragm are exactly those of the conductive section of the driving means and wherein consequently the interest of such a counter-reaction system may be considerable.

With the various embodiments of my improved loud-speaker or microphone, the following further features are advantageously incorporated:

The front surface 6a of the diaphragm 1a is smooth in the manner of a plate, and its surface sizes, that is its length and its breadth when said surface is rectangular,

range between eight times and fifty times the thickness $e1$ of said diaphragm including its webs such as 15.

The actual breadth 13 of each web 15 ranges between 20% and 100% of said thickness $e1$ and the depth of each 5 web measured in the same direction as $e1$ ranges between 30% and 70% of $e1$.

The thickness of the diaphragm 1a without the webs, is such that the forces applied to its rear surface by the webs 15 starting from the conductive wire or ribbon may be transmitted without any substantial deformation to the correspondent point of the front surface 6a of said diaphragm, any point of said front surface being located through the actual structure of the diaphragm and its webs, within a virtual angle of less than 50° to either side of a line perpendicular to the rear surface, and passing through the point of application of the force to be considered. This arrangement is disclosed with further detail hereinafter, reference being made to FIG. 8.

The point of application of the force is to be understood 20 as the point at the root of a web, more particularly along its outer surface as shown at A or B in FIG. 3. It will be appreciated from a consideration of the embodiment of FIGS. 1-3 that since the thickness of the diaphragm from the front to the back surface is 2 mm., and the clear spacing 25 between the web is 4 mm. (these dimensions will be documented more particularly hereinafter) that an angle drawn from A or B to a point on the front surface of the diaphragm midway between the webs will be inclined at an angle of 45° whereby every point on the front 30 surface of the diaphragm will lie on the base of an isosceles triangle having base angles of 45° and a vertex located at points A or B.

The thickness of the diaphragm in FIGS. 1-3 is equal 35 to $e1$ minus the depth of the webs which as shown on page 5 is equal to 6 mm.—4 mm. or 2 mm. The spacing between the webs is specified at page 5 as being $l1$ which is 4 mm.

FIGS. 4 and 5 relate to a further embodiment of my 40 improved loud-speaker. The coupling is obtained by means of a rectilinear conductive ribbon 2d of which the plane registers with the medial plane of the gap between the magnet poles 3d and 4d inside which gap the ribbon is engaged. Said ribbon may be given any allowable 45 desired length, for instance 10 to 30 cm. or more. It is therefore inserted through one of its edges inside the gap of a corresponding magnet 3d, 4d. Near its other edge, it engages in a suitable manner the apex of a diaphragm 1d according to my invention, having a cross-section, the 50 shape of which approximates that of a triangle with a front surface shown at 6d, while its sides 8d and 9d converge towards the above-mentioned apex, thus forming advantageously an angle t of about 90° . The feed connections for the ribbon 2d thus held in the diaphragm are shown at 11d and the tongues for the suspension of the 55 coupling 1d are shown at 12d. FIGS. 6 and 7 show in full detail an advantageous embodiment of the connections 10d, which play the same part as 11d. Said connections 10d are formed by an undulating section 2d of the 60 loud-speaker driving means in a plane perpendicular to that of FIG. 7, together with the feed of current into the conductive ribbon 2d.

As to the suspension tongues 12d, they are advantageously made of a yielding and light material, as in the case of the tongues 12a and 13a illustrated in FIGS. 1 and 2. Said tongues connect the diaphragm with the 65 frame of the loud-speaker, or else with the case or baffle board of the latter if any, which is however no longer necessary in the case of loud-speakers according to my invention.

In all cases, the suspension tongues for the diaphragm of a loud-speaker or a microphone according to my invention should have desired yieldingness and/or elasticity so that the movements of said diaphragm may constitute 70 translational movements parallel with the corresponding planes of symmetry of the gaps in the magnets.

FIGS. 8 to 10 relate to an embodiment deriving from that of FIGS. 4 and 5. In said FIGURES 8 to 10, the electro dynamic coupling is performed by means of a wire or ribbon which is wound or formed into a rectangular or substantially rectangular shape, of which the longer sides 2e and 2f are several times longer than the breadth of the rectangle or substantially rectangular figure corresponding thereto. These two larger sides 2e and 2f are inserted respectively in one of the two gaps extending between the poles, 4e on the one hand, and 3e, 5e of a magnet on the other hand. The remainder of the embodiment is substantially the same as in the case of FIGS. 4 and 5, except as concerns the transverse cross-section of the diaphragm 1e; said cross-section is in the present case substantially that of an isosceles trapezium of which the smaller base forms a section of the rear surface of the diaphragm. Near the ends of said smaller base, are fitted the sections 2e and 2f of the operative conductive ribbon, which is fed by two connections 10e made of a further pleated ribbon, of which the mean plane is perpendicular to the plane of the rectangular structure 2e and 2f. Considering a predetermined length of the diaphragm 1d or 1e (measured perpendicularly to the plane of FIGURES 4 and 8), the front surface of the diaphragm 1e of FIG. 8 may have an area which is substantially double that of the diaphragm 1d of FIG. 4, said diaphragm remaining furthermore perfectly rigid and faithful, taking into account the fact that the geometrical conditions as to the angles are observed in this case in a manner similar to that which has been disclosed for a similar purpose, in the case of the embodiment of FIGS. 1 to 3. This may be explained in a clearer manner as follows (FIG. 8): the forces being applied to the points A and B of the rear surface 7e of the diaphragm, by the conductive ribbons 2e and 2f, any point P whatever on the front surface 6e of the diaphragm lies within a vertical geometrical angle (which therefore does not correspond to a material structure inside the diaphragm), which angle is equal at a maximum to 50° to either side of the perpendiculars AB or DE to said rear surface passing through said points A and D. In the case of a point P (FIG. 8), it is apparent that the latter lies both in the angle $BAC=a$ and inside the angle $EDF=d$, these two angles being equal to less than 50°. Experience has shown that such a geometrical condition relating to all the points of the front surface of the diaphragm with reference to the points of application of forces on the rear surface of the latter corresponds to an absence of any substantial deformation of the diaphragm which appears then as quite rigid and incapable of moving without any deformation or phase-shifting with reference to its rear surface. This cooperates consequently in the obtention of high grade results by my improved loud-speaker or microphone, said high grade being even generally far superior to what could be obtained hereinbefore by loudspeakers or microphones of a comparable cost price.

The embodiment illustrated in FIGS. 11 and 12 is constituted by a combination of the arrangements according to FIGS. 2 and 8. The diaphragm 1g has a large area (the linear sizes of which may be equal to several times its thickness). The control of said diaphragm 1b is obtained by means of a conductive ribbon folded into the shape of a Greek pattern including successive parallel elements 2g, 2h, 2i, 2k etc. . . . as disclosed with reference to the wire 2a of FIG. 2, or else of the ribbons in the modifications proposed for the latter figures. Each of the long sides of this Greek pattern is inserted inside the corresponding gap of a magnet which is not illustrated, in a manner similar to what has been disclosed with reference to FIG. 8.

Lastly, FIGS. 13 and 14 relate to a loud-speaker according to the invention, wherein the coupling is obtained by means of a number of circular windings. In FIG. 13, are shown in particular two of said windings, 2m and 2n, positioned in the circular gaps of two corresponding mag-

nets 3m, 4m, 5m, and 3n, 4n, and 5n. In FIG. 14, four of said windings 2m, 2n, 2p, 2q are shown. Preferably the diameters of said windings (which are equal to, say 2 cm.) are substantially equal to one half of the spacing of their axes. The diaphragm is shown at 1m. It may have a large area as in the case of FIGS. 1 and 2; the linear sizes of said area depends merely on the number of windings such as 2m, 2n to be positioned on the rear surface 7m of said diaphragm, in a manner such that the latter may move rigidly as a unit and without any parasitic or distorting effects as already mentioned hereinabove.

Thus, whatever may be the embodiment adopted, my invention provides electrodynamic loud-speakers and microphones, executed in a novel manner and provided with substantial advantages among which I wish to mention more particularly the very large useful areas provided by the front surface of the diaphragm 1 which I obtain, in association with a faithfulness in the reproduction and/or in the coupling, which is far superior to what was usually obtainable hitherto; this invention also provides a very simple and sturdy structure of a comparatively low cost price, considering the high grade of operation and advantageous features reached.

As already mentioned, my invention is by no means limited to those applications or embodiments of its different parts, which have been more particularly disclosed and it covers, in contradistinction, all the modifications thereof, falling within the scope of the accompanying claim, and for instance, in case of an embodiment similar to that of FIG. 11, the open rectangular sections of the ribbon 2g, 2h, 2i need not be all interconnected, the successive longer sides of said rectangles being in fact, if desired, all independent of one another, and also it is possible to resort, as required, to sizes or numerical data which are different from those mentioned with reference to the examples disclosed chiefly in the case of the examples illustrated in FIGS. 1 to 3.

In the accompanying claim, the expression "electrodynamic apparatus" should be construed as including electrodynamic loud-speakers and electrodynamic microphones.

What I claim is:

Sound reproducing apparatus of the electrodynamic type comprising a diaphragm of expanded synthetic resin having a specific weight less than 0.1 gram per cubic centimeter, said diaphragm having a front and rear surface which are substantially parallel to one another, said front surface being a flat planar surface, said diaphragm including integral equally spaced rectangular webs extending rearwardly from the rear surface of the diaphragm and defining a series of equal spaces between adjacent webs, said webs being spaced apart a distance such that the spaces therebetween are substantially equal to the distance which each web projects from the rear surface of the diaphragm whereby said spaces between adjacent webs have a square profile, a continuous conductive element secured to said webs at a location remote from the rear surface of the diaphragm, means elastically supporting the diaphragm to permit rectilinear translational movement thereof and fixedly supported magnetic means including a plurality of magnetic elements equal in number to the webs and having magnetic gaps in which are accommodated respective webs, said magnetic means and conductive element constituting a magnetic circuit in which variations in the magnetic field of the magnetic elements produces corresponding displacement of the conductive element as well as the webs and diaphragm secured thereto, said diaphragm having a distance between the front and rear surface thereof which is related to the size of the spaces between adjacent webs such that every point on the front surface of the diaphragm lies on the base of at least one isosceles triangle having a vertex at the intersection of the rear surface of the diaphragm with the edges of the webs and including a vertex angle of less than 100° whereby the diaphragm will undergo sub-

stantially rectilinear translational movement as a result of variations in the magnetic field.
